UNITED STATES PATENT OFFICE.

KATHERINE L. DRUMMOND, OF CHICAGO, ILLINOIS, ASSIGNOR TO T. BUETTNER & CO.,
INC., OF CHICAGO, ILLINOIS, A CORPORATION OF ILLINOIS.

DESIGN FOR A UTENSIL MITT.

Application filed April 7, 1926. Serial No. 17,206. Term of patent 3½ years.

To all whom it may concern:

Be it known that I, KATHERINE L. DRUMMOND, a citizen of the United States, residing at Chicago, county of Cook, and State of Illinois, have invented a new, original, and ornamental Design for Utensil Mitts, of which the following is a specification, reference being made to the accompanying drawing, forming part hereof.

The figure is a plan view of a utensil mitt, showing my new design.

I claim:

The ornamental design for a utensil mitt as shown.

KATHERINE L. DRUMMOND.
